UNITED STATES PATENT OFFICE.

RALPH W. POPE, OF ELIZABETH, NEW JERSEY.

COMBINED PEN-CLEANER AND PAPER-WEIGHT.

SPECIFICATION forming part of Letters Patent No. 268,431, dated December 5, 1882.

Application filed April 4, 1882. (No model.)

To all whom it may concern:

Be it known that I, RALPH W. POPE, a citizen of the United States, residing at Elizabeth, in the county of Union and State of New Jersey, have invented a Combined Pen-Cleaner and Paper-Weight, of which the following is a specification.

The object of my invention is to provide a compact, economical, and effective device for 10 cleaning writing-pens and removing fibers of paper or other matter which may accumulate upon the nib of the pen when in use. The support or holder of the pen-cleaner is so constructed that the whole serves also as a convenient paper-weight for use upon a desk or 15 table.

In the accompanying drawings, Figure 1 is a plan view of my improved pen-cleaner and paper-weight, and Fig. 2 is a transverse vertical section therethrough.

Referring to Fig. 1, A represents a base or holder, which may be formed of any suitable metal or like substance, but is preferably of cast-iron. Its surface may be polished, 20 janned, plated with nickel, or otherwise suitably ornamented and finished. Within the base A is formed an open annular recess or seat B, best seen in Fig. 2. In the center of this recess is an upright post or projection, C, 25 perforated vertically by a screw-hole, g, into which fits a thumb-screw E, having a milled head or knob, e, which serves as a convenient handle. The post C projects upward nearly or quite to the same height as the upper surface or edge 30 of the base A. A flat coil or roll of paper ribbon, D, is placed within the recess B, the screw E being first removed to admit it. The coil is formed with a circular aperture in its center, which passes over the post C. The 35 shoulder f, upon the lower part of the milled head e of the screw E, serves as a clamp to secure the paper-coil D firmly in its proper position within the recess B. The coil D consists of a continuous strip or ribbon of bibulous paper, having a breadth preferably of about half an inch. The coil is wound, by any suitable means, with a uniform tension from the center of the coil to its outer periphery, care being taken to leave it sufficiently loose to

admit of a point of a pen being thrust between the convolutions. After the coil has been wound to the proper diameter, the outer end may be secured by pasting or otherwise. I have found in practice a coil about three inches in diameter to be a desirable and convenient size.

When a writing-pen becomes clogged by reason of an accumulation of paper fiber or other extraneous matter upon or between the points of its nib it may instantly be cleaned by 60 thrusting its point into the exposed upper side of the paper coil and again withdrawing it. The pressure of the adjacent convolutions of paper will remove all obstructive matter from the point as it is withdrawn. When the 65 writer has done using the pen, by thrusting the point of the same into the coil, the ink remaining thereon will be absorbed by the adjacent convolutions of paper, leaving the pen in a clean condition ready for subsequent 70 use.

The base or holder A is preferably constructed of sufficient weight and thickness so that it may serve as a paper-weight, in which case the milled head e of the screw E forms a convenient handle therefor.

It may be observed that the coil D, being 75 equally adapted to be used as a pen-cleaner on each of its sides, may, when worn or saturated with ink on one side, be inverted in the holder and the other side used. After the paper coil has become worn out from use it may be replaced by another similar one at a trifling cost.

I do not desire to confine myself to the precise form of construction shown in the drawings or to the dimensions recommended herein, as it is obvious that both may be varied without departing from the principle of the invention.

I claim as my invention—

1. A pen-cleaner consisting of a coiled strip or ribbon of paper provided with a base or holder, substantially as hereinbefore set forth.
2. The combination, substantially as hereinbefore set forth, of a coiled strip or ribbon of paper and a base having a recess formed therein for receiving or containing said coil.

3. The combination, substantially as hereinbefore set forth, of a coiled strip or ribbon of paper, a base having an annular recess formed therein for receiving or containing said coil, and a removable clamp for confining the paper coil within the recess.

In testimony whereof I have hereunto sub-

scribed my name this 31st day of March, A. D. 1882.

RALPH W. POPE.
